UNITED STATES PATENT OFFICE.

OSCAR L. WEIGERT, GEORGE G. GRAHAM, AND GEORGE F. ULLRICH, OF MISSOULA, MONTANA.

NON-REFILLABLE BOTTLE.

982,325.

Specification of Letters Patent. Patented Jan. 24, 1911.

Application filed April 21, 1909. Serial No. 491,325.

To all whom it may concern:

Be it known that we, OSCAR L. WEIGERT, GEORGE G. GRAHAM, and GEORGE F. ULLRICH, citizens of the United States, residing at Missoula, in the county of Missoula and State of Montana, have invented certain new and useful Improvements in Non-Refillable Bottles, of which the following is a specification.

- 10 This invention relates to bottles provided with means whereby, after having been once filled, they cannot be refilled, the invention consisting broadly in the provision of a plurality of valve seats in the neck of the bottle, and the association with each valve seat of a valve therefor, one of said valves of a solid and relatively heavy character so that when the bottle is in its ordinary position, said valve shall be seated and close the entrance 20 of the bottle, while the other valve is hollow, and therefore when the bottle is inverted for the unauthorized introduction of liquid, the valve will, by its buoyancy, rise to its seat, thereby closing the bottle against the introduction of said liquid.
- 25 For a full understanding of the invention and the merits thereof, and to acquire a knowledge of the details of construction, reference is to be had to the following description and accompanying drawing, in which:

Figure 1 is a partial vertical section of a bottle showing our improved valve arrangement; Fig. 2 is a view of the valves detached and before their insertion into the bottle; 35 and, Fig. 3 is a section on the line 3—3 of Fig. 1.

Corresponding and like parts are referred to in the following description and indicated in all the views of the drawing by the same reference characters.

Referring to these figures, 2 designates the body of the bottle which may be of any suitable or desired form. Above the body, the neck of the bottle is constructed in a 45 slightly conical formation, as at 3, so as to form a seat 4 normally occupied by a hollow valve 5. Above the seat 4, the neck is expanded, as at 6, so that the diameter of this expanded portion is greater than the diameter of the valve 5. Above the expanded portion 6, the neck is again contracted, as at 7, and is there provided with inwardly projecting ribs 8, the channels between said ribs providing for the passage of liquid when the 55 bottle is inverted and the valve 5 has rolled

down to the lower end of the expanded portion 6. The upper end of the contracted portion 7 forms a seat 9 for the ball valve 10 which is solid. Above the seat 9, the neck is again expanded, as at 11, to a diameter greater than the diameter of the ball valve 10 so as to permit the valve to easily move from its seat when the bottle is inverted. Above the expanded or globular portion 7, the neck is again contracted as at 12, and on its interior is provided with inwardly extending ribs 13 the spaces between which form channels for the passage of liquid when the bottle is inverted and the valve 10 has rolled down to the lowest end of the 70 globular portion 11.

14 designates a stopper of any suitable character which fits in the mouth of the bottle.

In order to initially fill the bottle, the 75 valves 5 and 10 are connected by a very fine and flexible wire 15 which may be attached to the valve 5 in any suitable manner, as by wax. This wire is preferably slightly corrugated and passes through an opening in 80 the valve 10. The object of this corrugation is to frictionally hold the ball valve 10 upon the wire in its proper location. When it is desired to initially fill the bottle, the wire 15 is drawn upward so that the balls 85 10 and 5 are lifted from their seats 9 and 11. Liquid can then be introduced into the mouth of the bottle, and will fill the body thereof. The wire is then drawn outward, breaking its engagement with the valve 5 90 and being pulled through the valve 9, thus leaving the two valves independent of each other and capable of resting upon their seats by gravity. It will be seen that the valves 5 and 10 will not interfere with the outward 95 passage of the liquid when the bottle is inverted, but that they will prevent any introduction of liquid into the body of the bottle. Thus, if the bottle is right side up, and it is attempted to introduce liquid, the valve 10 100 will be forced solidly against its seat, gravity itself acting to hold this valve to its seat, besides the actual force of the liquid being introduced. It is a common practice, however, to invert a bottle for the purpose of 105 filling it, and for this purpose, the solid ball would be of no value. The hollow ball, however, has sufficient buoyancy so that if the bottle be inverted, and liquid be introduced, the ball will float upward upon the 110

surface of the liquid until it finds its seat 4, thus closing the body of the bottle as effectually as did the ball valve 10.

While we have shown what we regard as a preferable form of our invention, we do not wish to be limited to the details, as the spirit of our invention may be embodied in other forms, without departing therefrom.

Our device is simple, relatively cheap and entirely effective for the purpose for which it was devised.

Having thus described the invention, what is claimed as new is:

The combination with a bottle having a neck provided with spaced superposed enlargements constituting valve-seats, upper and lower valves normally engaging said seats, the upper valve being provided with a vertically disposed wire receiving pas-

sage, and a valve unseating member formed of a single length of corrugated wire, one end of which is detachably secured to the outer surface of the lower valve and the other end thereof extended through the passage in the upper valve with the corrugations thereof frictionally engaging the walls of said passage, and a finger-piece secured to the free end of the valve unseating member for simultaneously lifting both valves from their seats.

In testimony whereof we affix our signatures in presence of two witnesses.

OSCAR L. WEIGERT. [L.S.]

GEORGE G. GRAHAM. [L.S.]
